Primary Examiner — George D. Kirschbaum*Assistant Examiner* — Lillian Embrey(74) *Attorney, Agent, or Firm* — Foley & Lardner LLP(57) **CLAIM**

We claim the ornamental design for an ear attachment for thermometer, as shown and described.

DESCRIPTION

FIG. 1 is a top perspective view of an ear attachment for thermometer;

FIG. 2 is a bottom perspective view thereof;

FIG. 3 is a front elevational view thereof; and

FIG. 4 is a rear elevational view thereof.

FIG. 5 is a left side elevational view thereof;

FIG. 6 is a right side elevational view thereof;

FIG. 7 is a top plan view thereof; and,

FIG. 8 is a bottom plan view thereof.

The broken lines are included for the purpose of illustrating portions of the ear attachment for thermometer and form no part of the claimed design.

1 Claim, 8 Drawing Sheets(56)
